UNITED STATES PATENT OFFICE.

JOHN M. KELLEY AND WARD E. PRATT, OF ROCHESTER, NEW YORK.

AIR-MOISTENING MEANS FOR FURNACES.

1,310,085.

Specification of Letters Patent.

Patented July 15, 1919.

Application filed July 27, 1918. Serial No. 247,061.

To all whom it may concern:

Be it known that we, JOHN M. KELLEY and WARD E. PRATT, citizens of the United States, and residents of Rochester, in the county of Monroe and State of New York, have invented certain new and useful Improvements in Air-Moistening Means for Furnaces, of which the following is a specification.

10 The present invention relates to air moistening means for furnaces, and more particularly to the type in which water is supplied automatically by a float valve to a water container subject to the heat of the 15 furnace, the water being evaporated and carried off with the hot air to moisten such air. An object of this invention is to provide a moistening means which is substantially universal in its application. Another 20 object of the invention is to provide a float valve which is of simple and inexpensive construction and may be readily adjusted to operate at different water levels. A further object of the invention is to provide a float 25 valve supported on a bracket adapted to be attached to any suitable container, and having the water supply connected to such valve in a manner that permits the valve to be located in any desirable place.

30 To these and other ends the invention consists of certain parts and combinations of parts all of which will be hereinafter described, the novel features being pointed out in the appended claims.

35 In the drawings:—

Figure 1 is a horizontal sectional view through a furnace equipped with the present invention;

Fig. 2 is a detail view of a float valve and 40 its supporting bracket, the float being removed;

Fig. 3 is a side view of the float valve;

Fig. 4 is a vertical sectional view through a furnace equipped with this invention;

45 Fig. 5 is a vertical sectional view through the float valve, the float being removed and the connection of the valve with its brackets being shown in detail;

Fig. 6 is a sectional view similar to Fig. 5 50 of another embodiment of the invention;

Fig. 7 is a detail view of the embodiment shown in Fig. 6, showing the float controlled valve member removed; and

Fig. 8 is a detail view showing the manner

in which the valve is connected to a water supply pipe.

Referring more particularly to the drawings, A indicates a furnace formed with a hot air chamber 1 surrounding a fire pot 2. In this hot air chamber a water container 3 is arranged, this container preferably being substantially in the plane of the fire pot 2 and having the form of a segment of a circle lying in proximity to and supported by the outer wall of the furnace, being spaced from said wall by rings 4. The amount of water in this container 3 may be ascertained from a tube 5 which extends upwardly from the container through the wall of the furnace and is open at its upper end. This tube may be rotatably mounted on the container 3 so that it may be turned downwardly to the position shown in dotted lines for the purpose of draining the container. A door 6 may be provided in the wall of the furnace adjacent one end of the container for the purpose of inspecting or repairing the float valve which is mounted in the container in a manner to be described. Preferably this end of the container indicated at 7 is enlarged so as to receive the float valve.

The float valve comprises preferably a valve member 8 of needle form having a rotary and an axial movement to coöperate with the valve seat 9 formed, in this instance, in a casing member 10, which has two bores 11 and 12 in axial alinement, the bore 12 having a larger diameter than the bore 11, and the seat 9 being formed at the junction of the bores. The walls of the bore 12 are interiorly threaded to receive the external threads of the stem 13 of the valve member 8, so that when the valve member is turned it also partakes of an axial movement toward and from the valve seat 9. Preferably the threaded connection between the valve member 8 and the casing member 10 comprises a plurality of threads of high or coarse pitch which will permit the valve member to move under pressure of the water 100 to its full open position after once being disengaged from its seat. The form of the valve end and the casing, together with the manner in which the valve opens, makes the valve self cleaning, as no small particles 105 can collect between the valve member and its seat. This valve member 8 may be controlled by a float 14 in the form of a ball at

one end of a stem 15, said stem having its inner end pivoted at 16 to a cross piece 17 rigidly secured to the stem 13 of the valve member 8. The stem 15 also has an arm 18 extending laterally from it at a point adjacent the pivot 16 and provided with a pin 19 adapted to operate within a curved slot 20^a formed in the cross piece 17. This arrangement gives a lost motion between the 5 float and the valve member 8 for the purpose of preventing slight inequalities in the level of the water from effecting the opening and closing of the valve, it being apparent that when the valve is closed the water may 10 recede slightly before the valve will be again opened, and when the opening does take place the action will be sudden, due to the fact that the water pressure will advance 15 the valve member ahead of the float.

20 It is desirable to make provision for the operation of the float valve at different water levels, and to this end the valve seat 9 is adjustable toward and from the valve member 8, preferably by mounting the casing member 10 so that it may be rotated, this rotation producing the relative movement between the valve seat and the valve member 8. To secure these results the casing member 10 may be mounted in a second 25 casing member 20, and be provided in its bore 12 with one or more ports 21, extending to an external annular groove 22 in the casing member 10. This annular groove registers with a discharge opening 23 formed 30 in the casing member 20 in any position to which the casing member 10 may be rotatably adjusted. A set screw 24 may be mounted on the casing member 20 to engage the casing member 10 in order to hold said casing 35 member to the casing member 20, and in adjusted position. In the embodiment shown 40 in Figs. 1 to 5, the casing member 10 may turn freely in the casing member 20, whereas in the embodiment shown in Figs. 6 and 45 7 the casing member 10 may be turned only after it has been disengaged from the casing member 20, as the external wall of the casing member 10 and the internal wall of the casing member 20 are provided with 50 registering ridges and grooves 25 which lock the casing member 10 against turning in the casing member 20 until the casing member 10 has been withdrawn axially from such casing member 20.

55 The casing member 20 may be formed separately from the supporting arm or bracket 26, or may be formed integrally with said bracket. In Fig. 5, the casing member 20 has a cylindrical portion 27 rotatable in a 50 sleeve 28 formed in the bracket 26. This arrangement permits the float valve to be turned with reference to the bracket so that the float may operate at different positions with reference to the bracket. A set screw 29 passes through the sleeve 28 to engage the

cylindrical portion 27, so as to hold the float valve in its adjusted position. In the embodiment shown in Figs. 6 and 7 this adjustment is not provided, as the casing member 20 is integral with the bracket 26. 70

The bracket 26 may be of any suitable construction, but it preferably proceeds laterally from the float valve and upwardly, its outer or upper end being provided with a hooked portion 35 adapted to engage over 75 the upper edge of a wall of the container 3, where it may be held by two set screws 36 operating within oppositely-extending lugs 37 formed on the sides of the arm, these set screws tending to hold the bracket firmly to 80 the container while at the same time permitting a slight lateral adjustment of the bracket or arm on the container the hook being employed as a fulcrum.

Water may be delivered to the float valve 85 by a supply pipe 30 which has a lateral port 30^a registering with a bore 30^b in a split collar 30^c clamped about the supply pipe. One member of the clamp has a nipple 30^d to which a valve 31 is connected. A flexible 90 tube 32 of small dimension is connected to the valve 31 and extended through the outer wall of the furnace. Within the furnace it is provided with a tapered nipple 33 fitting within a flaring seat 34 on the casing member 10, and held to said seat by a collar 36 which is provided with an internal shoulder engaging an external shoulder on the nipple and also with internal threads engaging external threads on the casing member 10. 100

The operation of the invention will be understood from the foregoing, but it may be summarized as follows: Water from the supply pipe 30 passes through the flexible connection 32 to the float valve which, when 105 there is no water in the container 3, is open. As the water rises in the container 3, the float 14 also rises and effects a turning of the valve member 8 to move the latter axially toward the seat 9, closing the valve. Should 110 it be desired to have the valve closed earlier or later, the casing member 10 is rotated in the casing member 20 until the desired closing position is secured, after which the set screw 24 is operated to hold the casing member 10 in its adjusted position. The joint 115 between the float valve and the supporting bracket permits the float valve to be turned, so that the float will occupy the most convenient position and the flexible connection 120 between the float valve and the supply pipe permits the bracket and the valve to be positioned at any desired place.

What we claim as our invention and desire to secure by Letters Patent is:—

1. A float valve comprising a screw threaded valve stem having a valve member at one end, a float connected to said stem to turn the latter, a rotatably mounted casing member in which the valve stem turns, provided 130

with a valve seat adjustable toward or from the valve member upon the rotation of the casing member to vary the position at which the float will cause the closing of the valve.

5 2. A float valve comprising a rotary and axially movable float-controlled valve member, a rotary casing member in which the valve member operates, formed with a valve seat, a surrounding groove and a port connecting said groove with the interior of the casing member, and a second casing member in which the first named casing member is rotatably mounted, having an opening adapted to register with the annular groove 15 of the first named casing member.

3. A float valve comprising a valve seat, a valve member having a screw threaded stem by which the valve is moved toward and from its seat, the threaded connection being such that the valve will move away from the seat under pressure after such valve has been loosened on its seat, and a float having lost-motion connection with the stem to loosen the valve on its seat and to close the 25 valve.

4. A float valve comprising a valve seat, a valve member having a screw threaded stem by which the valve is moved toward and from its seat, a cross piece on the stem, and 30 a float having a stem pivoted to the cross piece on one side of the turning axis of the

valve stem and having a pin and slot connection with the cross piece on the opposite side of said turning axis.

5. A float valve comprising a casing member provided with an outlet, a casing member having an inlet and an outlet and rotatably adjustable in the first named casing member while maintaining communication with the outlet of the first named casing member in its different positions of adjustment, a valve seat on the rotatably adjustable casing member, a valve for coöperating with the valve seat having a screw threaded stem operating in the rotatably adjustable casing member, and a float connected to said valve stem. 35

6. In combination with a float valve, a supporting arm for the valve having a hook for engaging a suitable container, said arm 50 carrying a pair of adjusting screws by which the arm may be adjusted laterally on the hook as a fulcrum.

7. In combination with a supply pipe, a flexible pipe connected with the supply pipe, 55 a container for the water, a bracket detachably connected to the container, and a float valve rotatable on the bracket about an upright axis and connected to the flexible supply pipe.

JOHN M. KELLEY.
WARD E. PRATT.
